INVENTOR.

T. H. Worrall

United States Patent Office.

THOMAS H. WORRALL, OF EAST BLACKSTONE, MASSACHUSETTS, ASSIGNOR TO THE AMERICAN TWIST-DRILL COMPANY, OF SAME PLACE.

Design No. 3,603, dated August 3, 1869.

DESIGN FOR A GRINDING-MACHINE.

The Schedule referred to in these Letters Patent and making part of the same.

To all whom it may concern:

Be it known that I, THOMAS H. WORRALL, of East Blackstone, in the county of Worcester, and State of Massachusetts, have invented a new and original Design for Grinding-Machine; and I do hereby declare that the following is a full, clear, and exact description thereof, which will enable others skilled in the art to make and use the same, reference being had to the accompanying drawing, forming a part of this specification.

The figure is a perspective view of my improved grinding-machine.

My invention has for its object to furnish a new and original design for a grinding-machine, which shall be ornamental, strong, and compact; and

It consists in the design hereinafter more fully described.

A is the base of the machine, which is rectangular in form, with its upper edges ornamented with a curved bevel.

B is the pedestal, which is made in the form of the frustum of a square pyramid. The sides of the pedes-

tal are panelled, and are made flaring at their upper and lower edges.

C is the stand, the middle parts of the side edges of which are ornamented with ornamental panelling and beading.

The ends of the stand are notched in their side edges, for the attachment of the rests D, which are also made ornamental, and in the form shown.

E are the bearings for the shaft F, that carries the pulley G and the grinding-wheels H.

The bearings E are made square, and ornamental upon their sides, as shown, and are surmounted with ornamental oil-cups I, as shown in the drawing.

Having thus described my invention,

What I claim as new, and desire to secure by Letters Patent, is—

The design for a grinding-machine, herein set forth.

The above specification of my invention signed by me, this 12th day of June, 1869.

Witnesses: THOS. H. WORRALL.

GEORGE A. WILBUR,
WM. H. JENCKES.
